OTTO P. AMEND, OF NEW YORK, N. Y.

PROCESS OF AND APPARATUS FOR CRACKING OR CONVERTING OILS.

Application filed June 8, 1917. Serial No. 173,666.

To all whom it may concern:

Be it known that I, OTTO P. AMEND, a citizen of the United States, residing in the city of New York, county of New York, and State of New York, have invented a certain new and useful Process of and Apparatus for Cracking or Converting Oils, of which the following is a specification.

This invention relates broadly to the art of cracking crude petroleum, heavy naphthas, kerosene, and higher-boiling hydrocarbon distillates or residuals, and converting the same into lower-boiling hydrocarbons, suitable for use in internal combustion engines, and for all other purposes for which the low-boiling petroleum distillates are used. The process is applicable either to hydrocarbons of the paraffin or of the naphthene or polymethylene series, or to mixtures of hydrocarbons of any series. The process is preferably applicable to any of the higher-boiling petroleum distillates, such as kerosene, Mexican distillates, gas oils, and fuel oils.

By my process I am able to secure any desired suitable vaporizing or cracking temperature within the hydrocarbons, at the same time that the sides and bottom of the still or digester are relatively cool, and the ability of the metal of the containing vessel to resist pressure is consequently not seriously impaired, and much higher pressures may safely be utilized than can be safely used by any process of external heating of oil in large stills. A pressure in excess of one hundred pounds may be safely used with large stills, of say from 600 to 1000 barrels capacity, with my process, whereas such pressures are not practicable on a large scale in any process in which the oil is heated by external heating. I secure this result by internal heating of the oil itself, by means of one or more high resistance electrical heating elements, preferably of carbon, and preferably wholly or partly immersed in the oil in the still or digester, and heated to the desired cracking temperature.

One of the chief difficulties hitherto experienced in attempts at cracking and converting high boiling hydrocarbons into a low boiling distillate, by the use of resistors submerged within the oil and heated to incandescence, consists in the fact that when the resistor was of any size and was heated to the high heat required for successful

cracking of the kerosene or other high boiling hydrocarbons, in the case of kerosene, a heat of from a cherry red to a white heat being generally required, the heated resistor repelled the oil and prevented intimate contact, and the oil at a distance from the resistor was merely vaporized without being cracked or converted into lighter hydrocarbons. The greater part of the condensate obtained was, therefore, unconverted oil. I have found that to overcome this repellent force of the heated resistors, and to enforce contact or close proximity of the oil or oil vapors with the incandescent resistors, pressure is required. The function of pressure in my process, while it incidentally raises the boiling point and the temperature of the liquid, and although it is primarily to enforce close contact between the oil or oil vapors and the highly heated incandescent resistors, it also largely arrests the gasification of the oil. The amount of pressure required in any particular case to produce the best results, depends on the character of the oil treated, and on the temperature of the resistors, and on the size of the receptacle. While a pressure of only from about two atmospheres upward may be used with kerosene in a very small retort, better results, both in the case of kerosene and other oils, are obtained from pressures considerably in excess of four to fifteen atmospheres. Generally small stills or retorts are preferred to large ones. It is obvious that the more pressure is applied to the oil to keep it in actual contact with the incandescent resistors, the more cracking and the less vaporization without conversion will take place, and that with an easily gasifiable oil pressures in excess of four atmospheres should preferably be used. With a gas oil or fuel oil, I prefer to use pressures of between six and ten atmospheres. Generally it is desirable that the higher the temperature of the resistors, the greater should be the pressure used, although with highly incandescent resistors pressures above ten atmospheres are unnecessary. Where the carbon or other high resistance conductor is heated to a bright red, or between a bright red and a white heat, pressures ranging from about 50 to 150 pounds to the square inch are preferable. Higher pressures are preferable to very low pressures, for the reason that the higher the pressure used, the more inti-

mate is the contact of the hydrocarbon liquid or vapor with the heated carbon or other resistance conductor, or source of heat, and the less gasification takes place and the more volatile and uniform is the resulting product. I have, however, successfully converted kerosene in a small retort into a low boiling hydrocarbon distillate by subjecting the kerosene to contact with carbon resistors, 5 of relatively large surface, heated by an electric current of about 2000 watts to a temperature corresponding to that of a bright red heat, under regulated autogenous pressures of the evolved hydrocarbon vapors 10 ranging from about two atmospheres up to ten atmospheres and over.

This electric heating element may be either entirely submerged or only partially immersed in the oil, or it may be entirely 20 above the surface of the liquid, or one or more of such electric heating elements may be either wholly submerged or partially immersed in the oil, and at the same time, one or more of such electric heating elements 25 may be inserted in a suitable space above the liquid to secure an intimate contact with the evolved hydrocarbon vapors. Where the electric heating element is wholly or partly above the surface of the liquid, all air should 30 first be removed, preferably by injecting an inert gas free from oxygen, such as hydrogen gas or natural gas. There is a distinct advantage in having one or more electric heating elements located above the surface 35 of the oil in the still or container, or partially submerged and partially above the surface of the liquid, as by this means more intimate contact is had between the heating element and the evolved hydrocarbon 40 vapors, and such liquid hydrocarbons as have only been vaporized without cracking or conversion into lighter vapors, because of the conduction of heat from the heating element in the liquid, are again subjected in 45 the vapor stage to contact with a second electric heating element, preferably electrically heated graphitic carbon, and are cracked and converted into low boiling hydrocarbon vapors before emerging from the still or 50 container. By this means, the percentage of low boiling hydrocarbons in the resulting condensate is greatly increased.

It is desirable that one or more of these 55 electric heating elements, preferably one or more electrically heated carbon tubes, of small diameter, should substantially fill a cross section of the vapor dome or the pipe or outlet leading to the condenser. In this way, all of the evolved hydrocarbon vapors 60 must pass in close proximity to the incandescent carbon.

I have found that high resistance conductors made of carbon are most satisfactory, both because of the saturated character of 65 the low boiling condensate obtained by their

use, and because any carbon resulting from the cracking of the hydrocarbons, on being deposited on the resistors does not affect them injuriously, whereas the formation of a hard carbon crust on metallic resistors, 70 impermeable to the hydrocarbon vapors, which usually takes place, seriously affects their successful operation. I prefer to use resistors of graphitic carbon as they are of higher resistance than ordinary carbon. 75 The high resistance conductor may be in the form of a rod, plate, sheet or tube or any other form. Of the above forms I prefer to use suitable hollow carbon tubes, 80 preferably made of graphitic carbon.

By the use of internal heat electrically applied, I am able to regulate to a nicety the actual heating within the body of the oil. This more perfect regulation of the heat 85 within the hydrocarbons enables a more constant quality of cracked product to be produced than is possible with external heating of the still.

The accompanying drawings illustrate 90 types of apparatus, forming part of my invention, which may be employed in practicing the process herein described, although I desire to have it understood that other forms of apparatus may also be used.

Referring to the drawings, Figure 1 95 shows, more or less diagrammatically, partly in section and partly in elevation, a substantially complete apparatus for practicing the process.

Figure 2 shows substantially the same type 100 of apparatus except that the pipe connecting the outlet of the still to the condenser is not inclined as it is in Figure 1, and, further, the pressure valve is in a different location, and

Figure 3 shows a still provided with a modified form of apparatus for heating the contents thereof.

Referring particularly to Figure 1, A is a still having an oil inlet a and an inlet for 110 inert gas b extending nearly to the bottom of the still. The still is heated by means of a submerged carbon resistor c, preferably in tubular form as shown, the said resistor being provided with suitable terminals d and e properly insulated from the walls of the still. The upper portion of the still 115 may also be provided with a carbon resistor f for subjecting the oil vapors to heat, said resistor being preferably in tubular form, 120 and being provided with suitable terminals g and h also properly insulated from the walls of the still. The outlet or gooseneck B of the still is inclined as shown, whereby a more or less reflux effect is obtained. The upper end of said gooseneck is provided 125 with a suitable pressure valve C, whereby the contents of the still and vapors therefrom may be kept at any predetermined pressure. The gooseneck of the still con- 130

nects with a cooling coil or condenser D, positioned within a cooling jacket or casing E, said jacket being provided with a suitable inlet *i* and outlet *j* for the cooling agent, such as water. The outlet *h* from the condenser leads to a suitable trap for condensed liquid collector F having a baffle *l* and a suitable draw-off pipe *m*. The trap is provided with an outlet *n* for non-condensed vapors or 10 gases, said outlet leading to a suitable compressor G, diagrammatically shown, wherein said vapors or gases are compressed, whence they pass through the outlet *o* of the compressor into an expansion chamber H. The 15 effect of expanding the mixture of compressed gases and vapors in chamber H results in a reduction of the temperature thereof to such extent that practically all the condensable vapors are liquefied in said 20 chamber and may be drawn off through pipe *p*. The expansion chamber H is provided with a gas or vapor outlet *q* through which the residuary, uncondensed vapors or gases 25 pass, whereupon they may be subjected to such further use or treatment as is found desirable.

Referring now to Figure 2, A' is a still having an oil inlet *a'* and an inlet for inert gas *b'* extending to nearly the bottom of the 30 still. The still is heated by means of a submerged carbon resistor *c'*, preferably in tubular form as shown, the said resistor being provided with suitable terminals *d'* and *e'* properly insulated from the walls of the 35 still. The upper portion of the still may also be provided with a carbon resistor *f'* for subjecting the oil vapors to heat, said resistor being preferably in tubular form, and being provided with suitable terminals *g'* and *h'* also properly insulated from the 40 walls of the still. The outlet or gooseneck B' of the still is substantially horizontal as shown and is provided, at its end adjacent to the outlet of the still, with a pressure 45 valve C'. The gooseneck of the still connects with a cooling coil or condenser D', positioned within a cooling jacket or casing E', said jacket being provided with a suitable inlet *i'* and outlet *j'* for the cooling agent, such as water. The outlet *h'* from the 50 condenser is provided with a pressure valve C' and leads to a suitable trap for condensed liquid, namely, collector F' having a baffle *l'* and a suitable draw-off pipe *m'*. The 55 trap is provided with an outlet *n'* for non-condensed gases or vapors, said outlet leading to a suitable compressor G', diagrammatically shown, wherein said vapors or 60 gases are compressed, whence they pass through the outlet *o'* of the compressor into an expansion chamber H'. The effect of 65 expanding the mixture of compressed gases and vapors in chamber H' results in the reduction of the temperature thereof to such extent that practically all the condens-

able vapors are liquefied in said chamber and may be drawn off through pipe *p'*. The expansion chamber H' is provided with a gas or vapor outlet *q'* through which the residuary, uncondensed vapors or gases 70 pass, whereupon they may be subjected to such further use or treatment as is found desirable.

Referring to Figure 3, A² is a still provided with an oil inlet *a²* and an inlet for inert gas *b²*. The still is heated by means of carbon electrodes *c² c³*, which may be of substantially the same form described in connection with Figures 1 and 2, the main difference in the method of heating consisting, 75 however, in spacing the electrodes apart, whereby arcing is produced within the body of the oil. The electrodes *c² c³* are suitably insulated from the still and are provided with suitable electrical connections *b³ b⁴*, 80 respectively. It will be understood that the still illustrated in Figure 3 may also be provided with means, similar to that shown in Figures 1 and 2 for electrically heating the oil vapors. To accomplish this 85 result, the outlet from the still may contain a suitable resistor *f²*, preferably in tubular form, having suitable terminals *g²* and *h²*.

From the foregoing description of the apparatus, its mode of use will be readily understood by those skilled in the art from the hereinafter detailed description of applicant's process. It will be observed that the pressure valves C, C' in Figures 1 100 and 2, respectively, are positioned intermediate the still and the condenser.

The pressure obtained is created by and is directly dependent upon the temperature of the resistors and therefore upon the 105 amount of electric current which is employed in the operation, and is produced by the vaporization, dissociation and expansion of the hydrocarbons.

In my process, the desired heat to produce 110 dissociation of the liquid hydrocarbons is applied directly within the liquid hydrocarbons, or their resulting vapors, by contact with or proximity to the heated resistors, the resistors being heated to any desired heat by the passage of a suitable electric current. The resistors may be entirely submerged within the oil, or may be partly above the liquid, so that the evolved hydrocarbon vapors, as well as the liquid hydrocarbons, may come in contact with heated resistors. By this means, a high local dissociating heat can be applied to the interior 115 of the hydrocarbon liquid or vapor, within the still or digester, without the necessity of first heating the metal of the still or digester itself, in order for the latter to transmit the heat to the hydrocarbons. The extent to which the metal sides and bottom of the still or digester will be heated, will de- 120 125 130

pend upon the amount of heat transmitted by the heated oil to the metal, instead of the heat required for vaporization being transmitted through the metal to the oil. By my process, the greatest heat is applied where it is most desired, that is, within the mass of oil or oil vapors.

Because of the capability in my process to combine high local dissociating heats within the oil, or its vapors, with moderate pressures I am able successfully to crack kerosene, that is, a hydrocarbon having a range of boiling points above 130° C. and below 260° C.

15 The cracking and dissociation of the hydrocarbons induced by the contact with the incandescent carbon resistors produces a very rapid evolution of low boiling hydrocarbon vapors and rapid resulting increase 20 of pressure. In order to obtain by my process a satisfactory conversion of kerosene into low boiling hydrocarbons, a small still should be used equipped with carbon conductors of relatively large surface in proportion 25 to the volume of oil, and the carbon resistors should preferably be heated to a bright red, or from a bright red to a white heat, although heats as low as a cherry red may be used with inferior results. Where 30 carbon resistors are used heated to the above heats, there is comparatively little formation of tar and evolution of gas, the deposited carbon being porous and flaky and easily removable, and the higher the temperature 35 of the carbon resistors, the lighter in gravity is the condensate, and the freer it is from olefines and other unsaturated hydrocarbons, and from coloring matter.

In general, with all the hydrocarbons, the 40 lower the boiling points, the higher is the dissociating temperature which should be used. Dissociation temperatures for gas oils and fuel oils of as low as about 500° C., and as high as a white heat of carbon, may be 45 used, but with these high boiling oils I prefer to use temperatures from a cherry red to a temperature corresponding to that of a bright red heat of carbon, or approximately from 750° C. upwards. Pressures in excess 50 of four and under ten atmosphere as sufficient, although higher pressure may be used.

With graphitic carbon resistors, a current of relatively low voltage and high amperage should be used. The voltage preferably ranges between 10 and 25 volts.

The time required to begin dissociation of the hydrocarbons, is extremely short by my electrical process. Vaporization and dissociation begin almost instantaneously and the desired dissociation increases with increase in the pressure.

As the temperature of the metal digester was under 200° C. when the pressure was 65 at 175 pounds, it is practicable to build

digesters or stills which can stand a pressure, at such a heat, up to 500 pounds or more. It is not safe to operate large stills heated by external firing over a pressure of 200 pounds.

The amount of current required to produce a given heat in any case, will, of course, depend largely on the number, diameter, or thickness and length and specific resistance of the resistors used.

In heating the high resistance conductors, the following general rules should be observed. The resistance of a conductor varies directly with its length and inversely with its area in cross section. The rise of temperature in a given conductor is proportional directly to the square of the current strength, and to the specific resistance, and is inversely proportional to the cube of the radius, and to the emissive (radiative) power. The heat lost by the conductor by radiation is greater, the greater the difference between its temperature and that of the surrounding medium. A peculiarity of carbon is that when heated to bright incandescence, its resistance decreases about one-half. This tendency may be largely offset by increasing the length of the carbon conductor and so increasing the resistance. Graphitic carbon maintains a higher resistance, when heated, than ordinary carbon.

Where additional hydrogen gas or natural gas is used in the cracking operation,—because of the fact that the hydrogen gas carries off with it a considerable amount of finely divided hydrocarbon vapors which need compression in order to be recovered,—the cracked vapors are preferably first cooled, in order to condense the heavy hydrocarbons and the more easily condensed lighter condensate, and the remaining uncondensed vapors and gases, may then be mechanically compressed, preferably in the cylinders of a suitable gas compressor, to pressures generally in excess of one hundred pounds, and preferably to over two hundred and fifty pounds to the square inch, and then condensed, preferably, by rapid expansion, which expansion may be availed of in any suitable type of engine for accomplishing work.

The condensation in the condenser may be had at atmospheric pressure or under substantially the same pressure as in the still or digester. In the latter case the desired pressure is obtained by regulating a valve at the outlet end of the condenser coil, as shown, for example by C² in Figure 2 of the drawings. When the condensation is to be carried on, at atmospheric pressure, as soon as the pressure in the still or digester reaches the given point, a suitable valve in the vapor outlet is opened and releases the vapors to the condenser. By the very slight opening of the valve under pressure, a practi-

cally continuous current of vapors may be released to the condenser.

From the upper part of the still, and preferably from the upper part of the vapor dome or tower in the upper part of the still, an inclined conduit or runback preferably leads up to the condenser coil. This inclined conduit, while not necessary, is distinctly advantageous as it obviates the necessity of making the vapor dome or tower too high and produces the effect of increasing the length of the reflux condensation zone. The operation of the air cooled inclined conduit is to condense the heavier fractions of the distillate and automatically to return them to the heated zones of the still for further treatment. This inclined conduit may be of any desired length, preferably from twenty to forty feet long, its diameter depending upon the size of the still and the amount of vapors requiring to pass over in a given time. A suitable valve is placed at the upper end of the runback. By this means the heavier fractions of the distillate are subjected to condensation under pressure in the runback, and subjected again to the dissociating contact with the heated carbon, the lighter vapors passing through the valve upon the regulated pressure being reached and over to the condenser.

I have found that the effect of incandescent carbon resistors, in cracking kerosene and other higher boiling hydrocarbons under pressure, is most remarkable. In previous cracking processes for the treatment of kerosene and other high boiling hydrocarbons, very heavy gas losses are had, ranging from a minimum of twenty per cent for fuel oil to a maximum of sixty per cent for kerosene, and also heavy deposition of carbon. That is, the two end products of the hydrocarbon, viz, hydrogen and carbon, are formed in very considerable quantities.

The effect of the electrically produced heat applied to the hydrocarbons through the incandescent resistors, is to crack the kerosene and other heavy hydrocarbons and convert them into low boiling hydrocarbons with a minimum of gas losses and of carbon deposition, when even such high temperatures are used as would normally, by any process of external heating, completely decompose the hydrocarbon into fixed gases and carbon. In other words, the effect of the cracking of the hydrocarbon under pressure, by the use of highly incandescent carbon is highly protective to the liquid hydrocarbons. A further feature of my process is that the condensates obtained are composed almost wholly of saturated hydrocarbons, or of a minimum of unsaturated oxidizable hydrocarbons, even where the very high cracking temperatures are used.

The condensate obtained is a crude condensate which generally requires further treatment.

Where a saturated distillate, that is a distillate free from unsaturated hydrocarbons, is desired, the ordinary method of removing all unsaturated hydrocarbons by the use of cold concentrated sulphuric acid may be used.

By "high-boiling hydrocarbons," I mean to include all liquid hydrocarbons having boiling points about 150° C.

By "kerosene," I mean to include all fractions distilled liquid hydrocarbons, either crude or refined, having boiling points above 150° C. and below 250° C., or having a distillation range not substantially in excess of those limits.

In view of the foregoing disclosure, it will be obvious to those skilled in the art that my process may be carried out with different steps and with the assistance of different apparatus from that described, without, however, departing from the scope of my invention, and accordingly, I intend that all matter contained in the above description, shall be interpreted as illustrative and not in a limiting sense.

Having described the invention, what I claim is:

1. The process of converting oils having boiling points about 150° C. into a low-boiling hydrocarbon distillate, which consists in maintaining in engagement with a relatively stationary body of the liquid hydrocarbon to be converted a non-metallic resistance conductor, causing a low voltage, high amperage electric current to pass through such conductor to maintain it at an incandescent temperature of between a cherry red and a white heat, introducing a fixed gas, and subjecting the liquid hydrocarbon to a controlled pressure of its evolved vapors in excess of two atmospheres and below thirty atmospheres, and collecting and condensing the resulting cracked vapors.

2. In an apparatus for cracking or converting heavy hydrocarbons, a still adapted to contain a relatively large and relatively stationary liquid body of oil, a carbon resistor positioned within the still and adapted to contact with the liquid body of oil therein, means for passing an electric current through the resistor, means for introducing a fixed gas into the still, means for maintaining the still under controlled superatmospheric pressure, and means for withdrawing and condensing vapors from the still.

3. The process of raising the Baume gravity of oils, which consists in subjecting a relatively stationary liquid body of the oil, in a confined space, while introducing a fixed gas, to intimate contact with a carbon resistor in engagement with the oil and

heated to incandescence by the passage of an electric current, while subjecting both the liquid hydrocarbon and the evolved vapors to a controlled pressure in excess of two and 5 below thirty atmospheres, and collecting and condensing the resulting vapors.

4. The process of converting oils, which consists in electrically maintaining a large carbon tube resistor adapted to permit circulation therethrough at a decomposing incandescent temperature in local contact with a relatively stationary mass of oil, in a still, while maintaining a controlled pressure in excess of five atmospheres, upon the liquid hydrocarbon and its evolved vapors, and collecting and condensing the resulting vapors.

5. In an apparatus for cracking or converting heavy hydrocarbons, a still adapted 20 to contain a relatively large and quiescent liquid body of oil, a tubular carbon resistor positioned within the still and adapted to contact with the liquid oil over the relatively large area presented by the continuous 25 inner and outer surfaces thereof, means for passing an electric current through the resistor, means for maintaining the still under controlled superatmospheric pressure, and means for withdrawing and condensing 30 oil vapors from the still.

6. In an apparatus for increasing the amount of light hydrocarbon fluids obtainable from a given quantity of native hydrocarbon oil or residuum the combination, 25 with a closed retort for holding the materials, of electrical heating means located in said retort interior comprising a plurality of resistors, one of which is located in the retort space for fluids, and another in the 30 retort space for vapors, and an electric circuit including said resistors.

7. In an apparatus for cracking fluid hydrocarbons the combination, with a closed retort having a zone for fluids and a zone 45 for vapors, of a carbon resistor located in the fluid zone, another carbon resistor located in the vapor zone, and means for passing electric currents through both resistors.

8. The process of converting heavy hydrocarbon oils into low boiling hydrocarbon distillates consisting in subjecting a relatively stationary body of such heavy hydrocarbon oils, to direct contact with an electrically heated non-metallic resistor immersed in the body of oil, while the body of oil is kept 55 under pressure.

9. The process of converting heavy hydrocarbon oils into low boiling hydrocarbon distillates consisting in subjecting a relatively stationary body of such heavy hydrocarbon oils, to direct contact with an electrically heated nonmetallic resistor immersed in the body of oil, while the body of oil is kept under pressure, and refluxing the unconverted vapors.

10. The process of converting heavy hydrocarbon oils into low boiling hydrocarbon distillates consisting in subjecting a relatively stationary body of such heavy hydrocarbon oil, to direct contact with a carbon 70 resistor immersed in the body of oil electrically heated to a temperature between a red and a white heat while the body of oil is kept under pressure.

11. The process of converting heavy hydrocarbon oils into low boiling hydrocarbon distillates consisting in subjecting a relatively stationary body of such heavy hydrocarbon oil, to direct contact with a carbon resistor immersed in the body of oil electrically 75 heated to a temperature between a red and a white heat while the body of oil is kept under pressure and refluxing the unconverted vapors.

12. The process of converting kerosene into a low boiling hydrocarbon distillate consisting in subjecting a relatively stationary body of liquid kerosene, to direct contact with a non-metallic resistor immersed in the relatively stationary body of kerosene electrically heated to a temperature between a red and a white heat while the body of kerosene is kept under pressure.

In testimony whereof I have signed my name to this specification.

OTTO P. AMEND.
